UNITED STATES PATENT OFFICE.

FERDINAND J. HAGEN, OF NEW YORK, N. Y., ASSIGNOR, BY MESNE ASSIGNMENTS, TO EDWARD H. MILLER, OF SAME PLACE.

CIGAR-BUNCHING MACHINE.

SPECIFICATION forming part of Letters Patent No. 520,881, dated June 5, 1894.

Application filed October 2, 1890. Serial No. 366,852. (No model.)

To all whom it may concern.

Be it known that I, FERDINAND J. HAGEN, a citizen of the United States, residing in the city county, and State of New York, have invented a new and useful Improvement in Cigar-Bunching Machines, of which the following is a specification.

This invention relates to cigar-bunching machines, and more particularly those in which the loose filler is fed, as from a supply hopper, through a throat intermittently into a mold more or less cigar-shaped, and, after the tobacco in said mold is separated from the remainder, as by a knife, the bunch in the mold transferred to the rolling and binding mechanism, as instanced in a prior United States patent, No. 415,943, issued to me on November 26, 1889.

The main object of my improvement is to adapt machines of this character to making bunches of the long-filler; and to this end the invention consists of novel means for feeding the long-filler and packing it evenly in the mold, and in order that the invention may be fully understood, I shall first describe in detail the mode in which the invention is carried into effect and then point out its various features in the claims.

Reference is to be had to the accompanying drawings, forming a part of this specification, in which—

Figure 1 is a sectional side elevation of a long-filler cigar-bunching machine embodying my invention on the line X X Fig. 3. Fig. 2 is a side elevation of the said machine. Fig. 3 is a sectional plan view on the line y y, Fig. 1. Fig. 4 is a cross-sectional elevation on the line z z, Fig. 1. Figs. 5 and 6 are detail face and rear views respectively of one of the feed-blocks of the said machine. Fig. 7 is a face view of the mold-shell and contained mold-section, constituting the mold of the machine. Fig. 8 is a sectional plan view of part of the said mold-shell and mold-section, and of the feed-chute registering therewith, on the line 8—8, Fig. 7.

Like letters of reference designate corresponding parts in the several figures.

The hopper A for the supply of the loose long-filler is provided with a throat B opening 50 and extending downward from its bottom into a transversely extending chute G and with a rag-wheel C for keeping the filler in motion and the throat B from clogging. In both the front and rear walls of the depending throat 55 B are formed a number of longitudinal slot-like openings D in which I arrange face to face the serrated engaging ribs E² of two feed-blocks E, the openings at the end of the feed-blocks being constantly closed by spring- 60 plates attached to the feed-blocks, substantially as in my prior patent, No. 415,943, referred to. I give the opposing feed-blocks E a simultaneous laterally vibrating and longitudinally reciprocating motion, by mechanism to be described, so that, the feed-blocks being raised, they will first be contracted so as to grip therebetween the filler in the throat B, then moved downward so as to feed a part of the filler into the chute G, then separated 70 so as to release the filler, and then raised to seize the filler anew as before. To give this simultaneous motion to the feed-blocks E, they are fitted in the throat-openings D, as guides, to work both longitudinally and laterally and are extended downward on opposite sides of the chute G and thereat connected by pivotal links H.

To the backs of the opposing feed-blocks E, are pivoted two pairs of toggle-levers I J, arranged on opposite sides of said feed-blocks, the joints of which toggle-levers are connected by links K² with the corresponding arms K' of an angle lever pivoted at its angle to the frame-work of the machine and 85 having an arm K³, which follows a cam K⁴ on a revolving cam shaft K⁵, so that the joints of the toggle-levers are reciprocated vertically. Each of the toggle-levers I is formed with an upwardly extending arm I' 90 and a downwardly extending arm I², and each of the toggle levers J with an upwardly extending arm J' facing and corresponding to the said arm I', and a downwardly extending arm J² facing and corresponding to the arm I². 95 In each of the arms I' and of the arms I² is

fixed adjustably a screw L, which is arranged to engage as a stop a corresponding bearing on each of the arms J' and of the arms J² respectively. The arrangement and adjustment is such that as the joints of the pairs of toggle-levers I J, are raised by the links K² as before described, the pairs of toggle-levers I J, will first be straightened, throwing the opposing feed-blocks E apart on their link connections H until the adjustable stops L on the lower arms I² meet the corresponding bearings on the arms J², on which the feed-blocks E will cease to separate and will be raised, until the motion of the links K² is reversed by the cam K⁴; then the joints of the pairs of toggle-levers I J will be lowered, again bending the said pairs of toggle-levers and drawing the opposing feed-blocks together until the stops L on the upper arms I' meet the corresponding bearings on the upper arms J', when the feed-blocks will cease to approach each other and will be forced bodily downward. By adjusting the stops L on the arms I' and I², the play of the toggle-levers and hence the motion of the feed-blocks can be accurately regulated at will.

With the forward mouth of the chute G, into which the loose filler is fed intermittently by the feed-blocks E, as described, is adapted 30 to coincide and register normally, as best shown in Figs. 7 and 8, the mouth of a movable mold-shell M³, in which is fitted to slide a mold-section M², the face of which approaches the mouth of the shell at either end, 35 as shown, thereby forming, with the mold shell, a roughly cigar-shaped mold M.

As described in my prior Patent No. 415,943, wherein however the corresponding mold-section is shown as sectional instead of solid as 40 in the present instance, the mold M, after receiving and molding the loose filler from the chute G as hereinafter described, is arranged to carry the said molded filler, after separation by the knife M', to the rolling and binding mechanism, where the molded filler is deposited in the rolling apron by the mold-section M² plunging forward in the mold-shell M³.

In the chute G, is fitted to slide longitudinally to and from the mold M, a plunger n, 50 composed by preference of a plurality of laterally abutting yet separate longitudinal sections N, the several shanks N' whereof project rearward from the rear open end of the chute, and are mounted to slide longitudinally in corresponding tubular guides O of a carrier O', common to all. The shanks N' of the plunger-sections N are formed with shoulders N²; and in the rear ends of the guides O are screwed adjustable sleeves O², 55 through which the shanks N' extend, and between the shoulders N² and the heads of the threaded sleeves O², are placed coiled springs O³ to form an elastic connection between the carrier O' and the plunger-sections, 60 while on the ends of the shanks N' back of

the sleeves O² are screwed nuts O⁴, so that on screwing the sleeves O² in the carrier O' and correspondingly adjusting the nuts O⁴ on the shanks N', the tension of the springs O³, and hence the position and elasticity of the 70 plunger-sections N with respect to the carrier O' may be adjusted at will. By means of a cam P, cam-following lever P', links P² connecting the lever P' to the plunger-carrier O', and a weight P³, acting on the lever P' oppositely to the cam, I cause the plunger-carrier O', and plunger, immediately after each feed of tobacco into the chute G in front of the plunger as previously described, to drive before it the tobacco in the chute forward 75 into the mold M, and to be again retracted before another feed of tobacco into the chute. The described compensating sectional character of the plunger will cause it to yield to unequal resistance from the packing of the 80 tobacco in the mold, and hence form a bunch of equal density throughout, which is separated by the knife M and then transferred for binding, as before stated. By adjusting the plunger-sections and the tension of their 85 spring connections with the carrier, the plunger can be adapted to a bunch-mold of any shape, from a straight mold to molds having the shapes of different cigars.

The described character of the feeding and 90 plunging mechanism peculiarly adapts this machine for use with the long-filler, which is thereby fed and evenly bunched without previous preparation.

I claim as my invention—

1. In a feed-mechanism for cigar-bunching machines, the combination, with a feed-throat having openings in its opposite sides, of a pair of feed-blocks working face to face in said opposing openings, and means for imparting 105 to the feed-blocks a simultaneous longitudinal reciprocating and laterally vibrating motion, substantially as described.

2. In a cigar-bunching machine, the combination, with a mold, a chute into which the 110 loose filler is fed leading to said mold, a sectional plunger working in the chute, plunger-operating mechanism and elastic connections between the plunger-sections and the plunger-operating mechanism, substantially 115 as described.

3. In a cigar-bunching machine, the combination, with a mold, a chute leading to said mold, a sectional plunger working in said chute, plunger-operating mechanism, and means for adjusting the plunger-sections independently with respect to the plunger-operating mechanism, substantially as described.

4. In a cigar-bunching machine, the combination, with a mold, a chute leading to said mold, a sectional plunger working in said chute, plunger-operating mechanism, elastic connections between the plunger-sections and their operating mechanism, and means for 125 130

adjusting the tension of the said elastic connections of the plunger-sections, substantially as described.

5. In a cigar-bunching machine, the combination, with a mold and a chute leading thereto, of a sectional plunger working in said chute, a reciprocating carrier in which the several plunger-sections are mounted to

slide, and elastic connections between said carrier and the several plunger-sections, substantially as described.

FERDINAND J. HAGEN.
